HUMIDIFIER AND AIR WASHER

Filed March 2, 1932

UNITED STATES PATENT OFFICE

2,002,553

HUMIDIFIER AND AIR WASHER

Herbert J. Somers, Detroit, Mich.

Application March 2, 1932, Serial No. 596,195

4 Claims. (Cl. 183—25)

My invention relates to a new and useful improvement in a humidifier and air washer whereby air may be delivered to rooms and similar compartments in a correctly humidified and thoroughly washed condition. It is an object of the present invention to provide an apparatus of this class in which the air to be circulated may be passed over a maximum area of moist surface contained within a minimum space, so as to render an efficient apparatus which is compact and of such a structure as to require a minimum space.

It is another object of the present invention to provide an apparatus of this class in which the air to be circulated or washed is caused to travel in a direction opposite to the travel of the washing spray, or directly against the spray.

Another object of the invention is the provision of a structure in which the plates which are maintained in a moist condition and over which the air is directed are maintained at all times in a clean condition.

Another object of the invention is the provision of a structure whereby the washing spray will serve to maintain the surface plates in clean condition.

Another object of the invention is the provision of a plurality of separating plates so that the air is thoroughly cleaned as well as humidified.

Another object of the invention is the provision of an air conduit so constructed and arranged that all noise arising from the operation of the washing and humidifying apparatus and the travel of the air is eliminated.

Other objects will appear hereinafter.

The invention consists in the combination and arrangement of parts hereinafter described and claimed.

The invention will be best understood from a reference to the accompanying drawing which forms a part of this specification and in which,

Fig. 1 is a central vertical sectional view of the invention.

Fig. 2 is a fragmentary sectional view taken on line 2—2 of Fig. 1.

Fig. 3 is a sectional view taken on line 3—3 of Fig. 1.

Fig. 4 is a fragmentary sectional view taken on line 4—4 of Fig. 1.

In the invention I provide a housing 9 resting upon a bed 10 of suitable sound deadening material. This bed is supported upon the bars 13 which are attached to the supporting legs 12. Resting upon the base 11, so as to occupy the lower section 15 of the housing 9 is a humidifying unit consisting of the spaced plates 14 connected

by the end walls 7 and 8. An opening 16 communicates with the section 15 so that air may be delivered thereto through the air duct 17.

A cover or hood 18 is mounted on the upper end of the housing 9 and lined with a layer 19 of felt or other suitable sound deadening and absorbent material. An outlet opening 20 is formed in the side of the hood communicating with the housing 21 in which is located a suction fan 22 by means of which air may be drawn upwardly 10 through the housing 9 and directed outwardly through the conduit 43 into the muffler 44 which is lined with a layer of suitable absorbent and sound deadening material 45. A concave, centrally positioned baffle 46 is mounted in the muffler 15 44 and provided on its under surface with a layer of sound deadening absorbent material 47. Additional baffles 48 and 50, each covered on its lower surface with a layer of sound deadening and absorbent material 49 and 51 respectively are 20 mounted above the baffle 46 and at opposite sides of the muffler 44, the baffle 50 being positioned above the baffle 48. This muffler communicates with the air delivery pipe 52 by which the air is delivered to the room or compartment for 25 which it is intended and from which, in the most common installations, it is withdrawn for treatment.

The blower 22 is driven by the electric motor 23 which is supported on the pedestal 24 mounted 30 on the base 25 which rests upon the angle iron 26 and the leg 27.

A water delivery pipe 28 which connects to a source of water supply under pressure, such as the city water supply, serves to deliver water 35 through the filter 29, the electrically controlled valve 30 and the pipe 31 to the outlet or spray nozzle 32, from which the water is directed downwardly in a spray on the humidifying plates 14. The plates 14 are thus kept moist and the incoming air which is drawn into the housing 9 by the blower 22 is caused to pass over these plates and through the spray 33. It will be noted that the travel of the air is in the opposite direction to the travel of the water spray and against the same. 45 It will also be noted that the spray is directed against the humidifying plates. This construction is one which assures a thorough cleansing and washing of the air and the humidifying 50 plates are always maintained in a clean condition, free from any accumulations or dust or other foreign material. The water is permitted to drain from the housing 9 by means of the drain pipe 34.

In the operation of the device I use an electric control embodying a humidistat 35 which is electrically connected to the switch housing 37 by means of the wire 36. The control switches in the housing 37, which are operated by the humidistat, are connected by the cable 38 to the motor 23 and by the cable 39 to the magnetically operated valve 30, so that the device may be entirely automatic in its operation. When the humidity 10 in the room which is being air conditioned drops to a predetermined degree the humidistat will operate to automatically set the device into operation.

Positioned in the housing 9, between the humidifying plates 14 and the blower 22, is a separating unit comprising the plates 42 which are formed sinuous and which are maintained in spaced relation to each other through the connection of the ends thereof with the end plates 53 and 54. These 20 plates, thus connected together, form a separating unit which divides the air current into separate streams and which also serves to separate therefrom any particles of dust or other solid foreign material which may have passed through the spray 33. This separating unit occupies the section or space 40 of the housing 9 and rests upon the angle iron supports 41.

With an apparatus of this nature, constructed and operated as described, there is provided a 30 simple and effective means for washing air and removing dust, foreign materials and odors therefrom and at the same time restoring the proper humidity to the air. The humidifying plates, being maintained in a clean condition, need 35 rarely be removed, so that there is provided a device of this class which, when once installed, will require very little attention and servicing. The humidifying plates are enclosed in a small enclosure or cabinet which is formed by the section of the housing occupied, so that a compact structure, with a maximum amount of moistening or humidifying surface in a minimum of space, is provided. Owing to this compactness and the small floor space occupied, and also owing to the 40 substantial absence of all noise, the economical structure of the device and the small expense at which it may be operated, the device is admirably adapted as an installation for air conditioning in dwellings and small buildings.

50 While I have illustrated and described the preferred form of construction I do not wish to limit myself to the precise details of structure shown but desire to avail myself of such variations and modifications as come within the scope of the appended claims.

Having thus described my invention what I claim as new and desire to secure by Letters Patent is:

1. In an air conditioner of the class described, 60 a housing having an air inlet and an air outlet, said inlet and said outlet being spaced apart; a humidifying unit located between said inlet and said outlet in the path of travel of the air; means

for causing air to enter said housing at said inlet and pass therefrom through said outlet; spray delivery means for delivering a spray of moistening medium on to said unit and against the direction of travel of the air through said housing; a hood for said housing; and a layer of sound deadening and moisture absorbing material covering the inner surface of said hood and exposed to the air traveling therethrough.

2. An air conditioner of the class described, 10 comprising: a housing having an inlet opening at one end; a hood for the opposite end of said housing having an outlet opening formed therein; means for effecting a travel of air through said housing into the same through said inlet opening and out of the same through said outlet opening; a spray delivery means for delivering a spray of moistening medium into said housing; and a layer of sound deadening and moisture absorbing material on the inner surface of said hood and exposed to the air traveling therethrough.

20 3. In an air conditioner of the class described, a housing having an inlet opening adjacent its lower end and an outlet opening adjacent its upper end; a humidifying unit at the lower end of said housing positioned in the path of travel of the air through said housing, said unit comprising a plurality of flat spaced plates with planal faces extended in vertical position; and a spray delivery means in said housing above said unit for delivering a spray of moistening medium downwardly against the path of travel of the air and on to said plates for moistening the air and maintaining the face of said plates in clean condition.

35 4. An air conditioning device of the class described comprising: a housing having an inlet opening and an outlet opening; means for effecting travel of air through said housing and outwardly therefrom through said outlet opening; a humidifying element positioned in said housing, 40 in the path of travel of the air passing therethrough; spray delivery means extending into said housing for delivering a spray of moistening medium thereinto and upon said humidifying element; a separating unit positioned in the path of travel of the air after passage of the same over said humidifying element for separating solid particles of water from the air passing thereagainst; a conduit for reception of the air passing from said housing; a muffler communicating 45 with said conduit; a concave centrally positioned baffle in said muffler having its convex face directed against the direction of travel of air passing therethrough; a layer of moisture absorbent and sound deadening material on the convex face of said baffle; additional baffles projecting inwardly from the sides of said muffler; and a layer of moisture absorbent and sound deadening material on one side of each of said additional baffles, 50 said layers being directed toward and exposed to the air passing therethrough.

HERBERT J. SOMERS.
